UNITED STATES PATENT OFFICE.

MICHAEL M. IMSHENETSKY AND JOHN I. GROMEEKO, OF SAN FRANCISCO, CALIFORNIA; SAID GROMEEKO ASSIGNOR TO DIMITRY MICHAEL IMSHENETSKY, OF SAN FRANCISCO, CALIFORNIA.

BUILDING CONSTRUCTION.

Application filed August 29, 1927. Serial No. 216,202.

Our invention relates to improvements in building construction, and surfacing plates therefor, wherein fabricated plates are rigidly clamped in abutting and partially overlapping relation upon a building frame to form finished inner and outer surfacings.

5 The present invention is an improvement upon our co-pending application, Serial No. 143,160, filed October 21, 1926, the primary 10 object being to provide a simplified and improved construction.

Another object is to provide an improved 15 building construction by which surface plates may be more easily and economically applied.

A further object is to provide an improved construction wherein surfacing plates are arranged to be held in closely abutting relation and in partially overlapping relation to 20 obtain a rigid and weatherproof surface.

A still further object is to provide an improved surfacing member which is relatively light and which may be readily handled.

We accomplished these and other objects 25 by means of the improved device disclosed in the drawings forming a part of the present application wherein like characters of reference are used to designate similar parts throughout the drawings and specification, 30 and in which,

Fig. 1 is a broken front elevation of a portion of a wall constructed in accordance with our invention, parts being broken away to show the construction in various planes;

35 Fig. 2 is a transverse section taken upon the line 2—2 of Fig. 1 in the direction indicated;

Fig. 3 is a broken rear elevation showing the inside surface of the wall surfacing 40 members;

Fig. 4 is a rear elevation of a surfacing member, drawn upon a larger scale and partly broken away and shown in section;

45 Fig. 5 is a left side elevation of the member as shown in Fig. 4, the lower portion being broken away and shown in section;

Fig. 6 is a broken sectional detail drawn 50 upon a still larger scale and showing the manner in which a turn buckle is connected to the frame portion of a surfacing member; and

Fig. 7 is a sectional detail showing the

manner in which adjacent plates are aligned.

Referring to the drawings, the numeral 1 is used to designate in general a suitable 55 building frame. Upon the inner and outer sides of the frame 1 we secure a plurality of surfacing members designated in general by the numeral 2.

Each surfacing member 2 consists of a 60 metal frame portion 3, constructed in rectangular form from inwardly faced channel members joined at their corners. Longitudinal and transverse braces 4 and 4' extend 65 across the frame 3, said members being preferably formed from rearwardly faced channel members intersecting at substantially the center of the frame. Upon each frame 3 is secured a surface plate portion 2' formed 70 from cement or other suitable material molded to embed spaced parallel reinforcing screens 6. The plate portions 2' are relatively thin and are secured to the frame preferably by bolts 5 engaging the screens 6 and frame and partially embedded in the cement. 75 The plate portions 2' are of substantially the same length and width as the frame portions 3, but are offset therefrom both longitudinally and transversely so as to overhang one side and end of the frame and to uncover 80 the opposite side and end of the frame a corresponding amount.

The plates 2 are secured upon the frame 1 in any suitable manner, preferably by means of wires or other securing elements 7 extending 85 across an adjacent frame member and connected between links 8 connected to the frame, said securing elements 7 being twisted or otherwise tightened to bind the plates firmly to the frame.

90 The frames 3 are provided with clamping discs 9 secured within the intersection of the braces 4 and 5, said discs being provided with outwardly disposed extensions 11 arranged to receive the ends of stay rods 12 95 threaded to receive turn buckles 13. The stays 12 extend through openings 14 formed within the sides and ends of the frame 3 in alignment with the braces 4 and 5, the openings in one member 2 being arranged to substantially register with the openings in members at the sides and ends thereof. The stays and turnbuckles extend longitudinally 100 and transversely between each member 2

and the members 2 adjacent the ends and sides thereof whereby the members may be clamped in firmly abutting relation.

In applying the surfacing members 2 upon a frame 1, the members 2 are laid with the overhanging portions of the plates 2' overlapping the frame portions 3 of the member immediately below and the member at one end thereof. The turnbuckles are then applied and tightened to draw the members 2 closely together, the frame portions 3 and the plate portions 2' being clamped into abutting relation at the same time. The members 2 are laid in successive rows and tiers in this manner, each member being secured to the frame 1 and clamped in turn to the adjacent members previously laid, whereby a rigidly bonded surfacing is applied upon the inner and outer surfaces of the building frame 1. A thin coating of cement or other bonding material is preferably applied between the overlapping edges of the plate portions 2' and frame portions 3, said cement being adapted to set to permanently seal the junctures between adjacent plates.

In order to insure accurate alinement of the members 2 and to obtain a perfectly smooth surface, alining blocks 16 are threaded onto the stays 12 and arranged to engage the registering openings 14 between adjacent plates, the blocks 16 being provided with squared heads 17 whereby the blocks may be turned by a suitable wrench or other tool to advance said block along the threads of the stay and to force the members 2 into perfect alinement.

Turnbuckles 18 are preferably connected between the clamping discs 9 of opposing members 2 upon opposite sides of the frame 1, thereby bonding the inner and outer surfacings together and assisting and securing the members upon the frame 1.

The members constructed as above described, are relatively light so that the plates 2 may be handled and applied by one or two men working alone. At the same time, the structure is thoroughly fire and weather proof, and presents a smooth and attractive appearance both from the inside and outside so that further finish need not be applied. The members 2 are not depended upon as any portion of the supporting structure of the building and hence produces a light and durable structure.

While we have illustrated and described the preferred embodiment of our improved construction, numerous modifications may be made in the various features without departing from the spirit of our invention. We therefore do not wish to restrict ourselves to the specific form and arrangement shown and described, but desire to avail ourselves of all modifications which may fall within the scope of the appended claims.

Having thus described our invention what

we claim as new and desire to secure by Letters Patent is:

1. A building construction comprising a frame; a plurality of surfacing members secured upon the frame, each member consisting of a metal frame and a surface plate formed from cement, molded to embed spaced parallel reinforcing screens, secured upon the outer face of the metal frame. 70

2. A building construction comprising a frame; a plurality of surfacing members secured upon the frame, each member, consisting of a metal frame and a surface plate formed from cement, molded to embed reinforcing screens, secured upon the outer face 80 of the metal frame; and means connected between the metal frames of adjacent surfacing members for clamping said members into abutting relation.

3. A building construction comprising a frame; a plurality of surfacing members secured upon the frame, each member consisting of a metal frame, and a surface plate formed from cement, molded to embed reinforcing screens, secured upon the outer faces 90 of the frame; and turn buckles connected between the metal frames of adjacent surfacing members for clamping said members into abutting relation.

4. A building construction comprising a frame; a plurality of surfacing members secured upon the frame, each member consisting of a metal frame, and a surface plate formed from cement, molded to embed reinforcing screens, secured upon the outer faces 100 of the frame; and turn buckles connected between the metal frames of adjacent surfacing members for clamping said members into abutting relation, and means mounted in connection with the turnbuckles and engaging the adjacent edges of adjacent metal frames for alining the surfacing members. 105

5. A building construction comprising a frame; a plurality of surfacing members secured upon the frame, each member consisting of a rectangular metal frame, and a surface plate formed from cement, molded to embed reinforcing screens, secured upon the faces of the frame, said plate being offset from the frame longitudinally and transversely to overhang one side and end of the metal frame and to overlap the side and end of the metal frames of adjacent members; and turn buckles connected between the metal frames of adjacent surfacing members 110 for clamping said members in abutting relation.

6. A building construction comprising a frame; a plurality of surfacing members secured upon the frame, each member consisting of a rectangular metal frame, and a surface plate formed from cement, molded to embed reinforcing screens, secured upon the faces of the frame, said plate being offset from the frame longitudinally and trans- 115 120 125 130

versely to overhand one side and end of the metal frame and to overlap the side and end of the metal frames of adjacent members; and turn buckles connected between the 5 metal frames of adjacent surfacing members for clamping said members in abutting relation, and means mounted in connection with the turnbuckles and engaging the adjacent edges of adjacent metal frames for alining 10 the surfacing members.

7. A building construction comprising a frame; a plurality of surfacing members secured upon the frame, each member consisting of a rectangular metal frame; and a surface plate 15 formed from cement, molded to embed reinforcing screens, secured upon the face of the frame; clamping discs secured at the centers of the metal frames; turn buckles connected longitudinally and transversely 20 between the clamping discs of adjacent members to clamp the members in abutting relation.

8. A building construction comprising a frame; a plurality of surfacing members secured upon the frame, each member consisting of a rectangular metal frame, and a surface plate formed from cement, molded to embed reinforcing screens, secured upon the face of the frame; clamping discs secured at 25 the centers of the metal frames; turn buckles connected longitudinally and transversely between the clamping discs of adjacent members to clamp the members in abutting relation; and means mounted in connection with 30 the turnbuckles for alining the surfacing members.

9. A building construction comprising a frame; a plurality of surfacing members secured upon the frame, each member consisting of a rectangular metal frame, and a surface plate formed from cement, molded to embed reinforcing screens, secured upon the faces of the frame; clamping discs secured at 40 the centers of the metal frames; and turn buckles having threaded stays connected between the clamping discs and extending through registering openings in the 45 edges of the metal frames for clamping the members in abutting relation.

50 10. A building construction comprising a frame; a plurality of surfacing members

secured upon the frame, each member consisting of a rectangular metal frame, and a surface plate formed from cement, molded to embed reinforcing screens, secured upon 55 the faces of the frame; clamping discs secured at the centers of the metal frames; and turn buckles having threaded stays connected between the clamping discs and extending through registering openings in the 60 edges of the metal frames for clamping the members in abutting relation; and alining members threaded onto the stays and engaging the registering openings for alining the 65 members.

11. A surfacing member for building construction comprising a rectangular frame; a surface plate consisting of a pair of spaced parallel reinforcing screens and cement embedding said screens to form a plate of substantially 70 the same length and width as the frame; and securing means set within the plates and arranged to secure said plate upon the frame.

12. A surfacing member for building construction comprising a rectangular frame formed from inwardly faced channels; centrally disposed intersecting longitudinal and transverse braces secured across the frame; a surface plate consisting of a pair of spaced 75 parallel reinforcing screens and cement embedding the screens to form a plate of substantially the same length and width as the frame; and means for securing the plate upon the frame. 85

13. A surfacing member for building construction comprising a rectangular frame form from inwardly faced channels; centrally disposed intersecting longitudinal and transverse braces secured across the frame; a 90 surface plate consisting of a pair of spaced parallel reinforcing screens and cement embedding the screens to form a plate of substantially the same length and width as the frame; and means for securing the plate 95 upon the frame, said plate being offset longitudinally and transversely to overhang one side and end of the frame.

In witness whereof, we hereunto set our signatures.

MICHAEL M. IMSHENETSKY.

JOHN I. GROMEEKO.
